RICHARD P. SIMMONS, OF NEW YORK, N. Y.

CORE BARREL WELL DRILLING APPARATUS

Application filed October 22, 1929. Serial No. 401,447.

The object of the invention is to provide a core barrel well drilling apparatus in which the core barrel is provided with cutting means and of a size to receive substantially all of the material removed by the cutting means; to provide a construction which provides for the operation of the core barrel by impact to impart axial movement thereto; and generally to provide an apparatus of the kind indicated which is of comparatively simple form and susceptible of cheap manufacture.

With this object in view, the invention consists in a construction and combination of parts of which a preferred embodiment is illustrated in the accompanying drawings, wherein:

Fig. 1 is a vertical sectional view through a well casing and the improved core barrel, showing the latter interlocked to the casing, against the relative rotative movement, showing the earth retaining means retracted.

Fig. 2 is a similar view, showing the earth retaining means extended.

Fig. 3 is a side elevation of the shiftable retaining device.

Fig. 4 is a side elevation of the earth holding tube which cooperates with the earth retaining device.

Fig. 5 is a side elevation of the improved core barrel.

Fig. 6 is an end elevation, taken on line 6—6 of Fig. 3, looking in the direction of the arrows.

Fig. 7 is a cross sectional view taken on line 7—7 of Fig. 1, looking in the direction of the arrows.

Fig. 8 is a sectional perspective view of the lower well casing section or head.

Fig. 9 is a transverse sectional view taken on line 9—9 of Fig. 1, looking in the direction of the arrows.

Fig. 10 is a transverse sectional view taken on line 10—10 of Fig. 2, looking in the direction of the arrows.

Fig. 11 is a vertical sectional view through a core barrel construction particularly to trap rock.

Fig. 12 is a similar view showing the rock retaining means in a different position.

Fig. 13 is a side elevation of the modified core barrel.

Fig. 14 is a similar view showing an external sleeve in a longitudinally shifted position.

Fig. 15 is a transverse sectional view taken on line 15—15 of Fig. 12.

Fig. 16 is a transverse sectional view taken on line 16—16 of Fig. 12, looking in the direction of the arrows.

Fig. 17 is a transverse sectional view taken on line 17—17 of Fig. 12, looking in the direction of the arrows.

Fig. 18 is a view, partly in longitudinal and partly in elevation, of combined well drilling units.

Fig. 19 is a similar view of another group of combined well drilling units.

Fig. 20 is another view of still another group of combined well drilling units.

Fig. 21 is a similar view of still another group of combined well drilling units.

Fig. 22 is a similar view of still another group of combined well drilling units.

Fig. 23 is a similar view of still another group of combined well drilling units.

Referring to the accompanying drawings illustrating the invention in detail 5 designates a well casing, the lower section 5' of which will be termed the head section, and 80 which is constructed with a tubular wall 6 having a series of longitudinally extending integral keys 7 and a series of longitudinally extending keyways 8, radially spaced therefrom, and coextensive with the keys 7. The 85 keys 7 are formed with transverse keyways 7a, which extend in the same circumferential zones, thus providing interrupted keyways to receive locking elements capable of being interlocked therewith by a relative rotative 90 movement. The elements for accomplishing this locking action are not shown in this application, but involve special keys which are movable in keys formed in a follower head which is constructed to be longitudinally interlocked with the well casing.

The upper end portions of the keys 7 are formed with tapered end portions 7' and the lower end portions thereof, are also formed with tapered end portions 7''.

100

In the head section of the well casing the core barrel 9 is interlocked against relative rotative movement, but to permit of relative longitudinal sliding. This barrel comprises 5 the tubular wall 10, and the annular coupling head 11 which is connected to the lower end of the tubular wall 10 by means of the threaded joint 12. This coupling head or member is provided on its lower end with 10 threads 13, which are shown to be of an internal type, to which the drilling head 14, carrying expansible drill bits 15, may be coupled and uncoupled. The threads 13 may, obviously, be of an external type, in 15 which case the corresponding threads of the coupling head would be internal.

The tubular wall 10 is formed with a series of integral keys 16, which are radially spaced from each other to form longitudinal keyways 17 between said keys, these keys and keyways being spaced radially from each other to interlock in all positions with the radial keys and keyways of the well casing head section. Both the lower end portions 25 16a of said keys 16 and the upper end portions 16b thereof, are tapered, so that they will readily pass the internal keys 7 of the well casing head section.

There are phases of well drilling when it 30 is desirable that the core barrel 9 be interlocked directly to the well casing head section, and there are other phases of well drilling when it is desirable to lower the core barrel below the well casing, and in order that the 35 core barrel may be adapted for each of these phases, a sleeve 18 is mounted over the tubular wall 10, by means of the screws 18a. This sleeve is formed with a series of triangular projections 18b, which are radially spaced 40 from each other to provide recesses to receive the tapered ends 16b of the keys 16 of the barrel 9.

The upper end of the tubular wall 10 is threaded to the head 19. The screws 18a are 45 threaded into this head or end wall 19 above the threaded connection of the same with the tubular wall 10. This head is provided with an annular recess 19a having internal screw threads 19b on one wall thereof, in which 50 the external screw threaded upper ends 20a of the longitudinal bars 20 of the core barrel tube 21 are connected. The arms or bars 20 are formed integrally with the core barrel tube, and are spaced radially from each other 55 equal distances, and this provides radial and longitudinal slots 21a therebetween. The bars 20 are nearly one half the total length of the tube, the lower half portion of which is shown to be imperforate, except near the 60 lower end thereof, which is shown to be provided with a series of radial slots or openings 22 in the annular wall of said tube. These openings or slots are located in the same longitudinal zone.

65 Within the split upper part of the core

barrel tube 21 the earth retaining device 23 operates. This device consists of the end wall 24a and the radially spaced flexible earth retaining bars or strips 24b, 24c and 24d. These flexible strips are spaced apart 70 so that they will radially interlock with the bars 20 and slide between the core barrel tube 21 and the annular wall 10. The lower end portions of these flexible strips or bars are adapted to enter the slots or openings 22 of the tube 21, from the outside of said tube, so that they may be forced into radial overlapping positions inwardly of said slots 22, thus providing a transverse earth supporting and retaining mattress below the core 80 crowded into the tube 21. The flexible strips 24b are shown to be somewhat longer than the flexible strips 24c, and the strips 24d are shorter than the strips 24c so that they will not obstruct each other when shifted 85 to earth retaining positions across the tube 21, as shown in Figs. 2 and 10. The inner ends of the strips or bars 24b and 24c are formed tapered to assist penetration of the earth. 90

To the central portion of the end wall 24a of the earth retaining device 23, a ram or piston rod 25 is connected. This ram is equipped with a piston head 26 on its upper end, which works in the pressure cylinder 27, which is mounted against the head or end wall 19. This pressure cylinder is supplied with air or pressure fluid by means of the conduit or air line 28, which extends to the surface of the well. 100

By forcing the piston head 26 downwardly the holding strips or bars 24b and 24c will be forced from the uppermost positions shown in Fig. 1 to the lowermost positions, shown in Figs. 2 and 10. By forcing the piston upwardly the fingers may be withdrawn, but this operation is conducted only after the loaded core barrel tube 21 has been withdrawn from the well casing, by a hoisting operation to the surface of the well, and 110 there emptied.

To the head or end wall 19 a tubular wall 29 is coupled, as by the screw joint 29a, and to the upper end of this tubular wall 29 the head 30 is coupled, as by the screw joint 30a. 115 To the underside of this head 30 a carrier plate or metal disc 31 is mounted, as by the bolts 32, and through this plate or disc the supporting rods 33 are slidable. The lower ends of the rods or bolts 33 are fixed to the head of the hammer 34, which includes the pressure cylinder 35, in which the reciprocating hammer or piston 36 works, and the valve 37 for controlling the direction of the stroke thereof. 120

This piston hammer 36 is adapted to strike against the head 19, which thus forms the anvil head of the core barrel. Coil springs 38 are mounted on the supporting bolts or rods 32, so as to cushion the rebound of the 125 130

piston hammer when it strikes against the anvil head 19. Air under pressure is supplied to the pressure cylinder through the valve 37, by means of the conduit 39, which 5 extends to the surface of the well.

A coupling head 40 is threaded in the head 29, and is provided with an externally threaded nipple 40a to which any other unit of the well drilling engineering equipment 10 may be coupled or uncoupled.

By removing the sleeve 18 the core barrel unit may be coupled to an underreamer unit and the two lowered through the well casing, and the core barrel unit supported by the 15 underreamer unit below the level of the lower section or head section of the well casing.

In Figs. 11 to 17, inclusive I show a modified form of the core barrel, wherein the use 20 of the flexible earth retaining strips or bars is eliminated and means used which develops a crowding action on the rock particles, which are wedged into the core barrel tube.

This construction includes the well casing head section 5', and a tubular wall 50 25 which is provided with longitudinal external keys 51 to interlock with the internal keys 7 of the well casing head section 5'. This tubular wall 50 is provided with an upper portion 50a which is somewhat thicker than the 30 lower portion 50b. To the upper portion 50a the anvil head 19e is coupled by the screw joint 50'.

The lower part of the anvil head 19e is 35 reduced and is provided with an annular recess 52, which ends at the shoulder 52a thereof, and which is widened at 52b. In this anvil head 19e the tubular wall 53 is coupled by the screw joint 53a. To the lower end of this tubular wall 53 a coupling head 54 is 40 connecting by the screw joint 54a and to the lower end of this coupling head 54 the tubular wall 55 is connected by the screw joint 55a.

The coupling head or union 54 is provided 45 with large external acme screw threads 54a which engage the acme threads 57a on the coupling ring 57 which embraces the head 54. The upper end of this coupling ring is connected by the screw joint 58a to the tubular wall 58, which is adapted to slide against the inner face of the tubular wall 50. The lower end of this coupling ring is connected by the screw joint 59a to the tubular wall 59, which slides in the tubular wall 50, and 55 which carries the tubular coupling head 60 on its lower end, by means of the screw joint 60a. On the coupling head 60 the drill head 61, carrying the drill bits 62, is detachably secured, as by the screw joint 62'.

In the upper end of the tubular wall 50 60 the tubular coupling head or union 63 is connected, as by the screw joint 63a. To the underside of this tubular coupling head the plate or disc 64 is connected by the bolts 65. 65 This plate or disc 64 carries the pressure

cylinder 66 by means of the bolts or rods 67 which slide through said plate or disc, and coil springs 68 are mounted on said bolts or rods. The lower ends of these bolts or rods are connected directly to the upper end of 70 the pressure cylinder 66, so that these springs will be placed under compression when the cylinder is subjected to a reaction. In this cylinder the piston hammer 69 works and operates through the lower end of the pressure cylinder against the anvil head 19e. 75 A valve 70 controls the flow of air or other pressure fluid to the pressure cylinder, so as to operate the same in both directions. Air is supplied to this valve by means of a conduit 71 which extends to the surface of the well.

Another coupling head or union 72 is connected to the head or union 63 by means of the screw joint 72a, and this head or union is 80 provided with an externally threaded nipple 72b, to which an underreamer or other unit of a well drilling equipment may be connected. A second conduit 71a is connected to the lower part of the valve and extends to the surface of the well. By controlling the flow of air through the conduits 71 and 71a the direction of the stroke of the piston hammer may be controlled at the surface of the well. 85 Any automatic type of air or pressure hammer, or other means for producing a percussive action against the anvil head 19e may be 90 employed.

The tubular wall 55 is equipped with a 95 ring abutment or stop 55b mounted upon it, which is designed to limit the upward movement of the two shiftable sections 53 and 55. The tubular wall 58 is provided with an abutment or limit stop 58b on its upper end which is designed to engage the shoulder 52a of the annular recess 52, and which is spaced downwardly from the extreme upper end of said tubular wall 58, so that said upper end will slide into and out of the recess 52. This tubular wall 58 is also provided with a ring 100 stop 58c which is adapted to be engaged by the acme screw coupling union 54 when the shiftable tubular wall sections 58 and 59 are at their limit of downward travel in the lower end portion 50a of the tubular wall 50. 105

The innermost tubular wall section 55 is 110 formed with a slot or opening 55c in its wall. The lower end 73a of the rock retaining lever 73 is adapted to be forced through this opening, and for this purpose said lever is pivoted at 73b upon the outer surface of the tubular wall 55, so that its upper end 73c will engage the spring 74, which serve to hold the lower end 73a of said lever in its outward position, or normally clear of the bore 115 of the tubular wall 55, which forms the core ball tube, together with the coupling union 54 and the upper tubular barrel 53.

When the well casing is rotated in a direction opposite to the usual direction of turn- 120

ing used in rotary drilling, and at the same time raised, the resistance offered by the drill bits 62 will be sufficient to cause the core barrel tube sections 55, 54, and 53, to turn 5 within the outer acme thread union 57, thus forcing the lower end 73a of said rock retaining lever 73 against the rock trapped in the combined core barrel tube, and thereby trapping the rock in the core barrel tube, due 10 to the engagement of the outer portions of the lever 73 with the integral cam shoulder 59c formed on the inner wall surface of the tubular wall 59.

The pinching action of the lever against 15 the rock core A is indicated in Fig. 15.

The tubular wall 50 is equipped with a detachable sleeve 75 which is secured in place by means of the screws 75a, and which performs the same function as the sleeve 18 of 20 the core barrel construction shown in Figs. 1 to 10, inclusive.

The interlocking longitudinal keys and 25 keyways formed in the well casing and the outer tubular wall of each of the core barrels, permit the turning of the well casing for drilling, so that the core barrel will rotate thereto, the said interlocking preventing relative rotative movement of the core barrel in the well casing, but permitting longitudinal movement, so that the core barrel may be reciprocated by being lifted and dropped 30 in the well casing, or subjected to a percussive action, by the operation of the pneumatic hammer, or other equivalent means 35 which may be employed for this purpose.

The core barrel well unit is adapted to be combined in line series with one or more well 40 operating units, by means of couplings between the respective adjacent units, and by 45 means of the interlocking keys and keyways between the lower or head section of the well casing and the uppermost unit of the series of units which are coupled in well line formation.

50 The particular grouping of well operating units will depend upon the particular geological and operating conditions encountered during the progress of a well drilling operation. The geological material always varies as the depth of penetration of the well increases, and this variation runs from soft materials to materials of various degrees of 55 hardness.

The slope of the strata also varies from 55 time to time, and the depth of the various layers of rock or other materials, changes as the depth of the well increases, and can never be accurately predetermined.

In Figs. 18 to 23, inclusive, I show an arrangement whereby various units are combined in well line formation, for simultaneously producing various steps necessary to the vertical deepening of the well.

Referring more particularly to Fig. 18, a 60 combination consisting of a motor head unit

100, an underreamer unit 101, and the core barrel unit 102, the latter embracing the detail construction shown in Figs. 1 to 10, inclusive of the present application.

The motor head unit 100 is equipped with 70 external longitudinal and parallel keys 100a, designed to interlock with the internal keys and keyways of the lower or head section 5' of the well casing, so that the lower end of the housing 100b, which is equipped with a threaded coupling union 100c, will extend below the lower end of the well casing head section 5'. To this coupling union 100c the upper end of the reamer unit 101 is connected. This reamer unit is equipped with 75 retractable and expandable reamer bits or tools 101a, which are shifted from retracted, or inoperative positions, to expanded and cutting positions by means of the piston rod 101b, and the toggle joint 101c, between the frames which carry said reamer tools or bits and said piston rod. This piston rod is operated by means of an air cylinder and pneumatic piston contained in the housing of said reamer unit, or by mechanical means enclosed 80 therein. The reamer unit is rotated by means of the motor enclosed in the motor head unit 100 at a reduced speed, by means of the reduction gearing connected thereto and also enclosed by the housing of said motor head unit 100. The motor is indicated at 100d, in the upper part of the housing 100b of said motor head unit.

The lower part of the housing 101d of the 85 reamer unit 101 is equipped with a coupling union 101e, to which the upper end of the housing 102a of the core barrel unit is connected. In this housing the earth trapping chamber 102b is provided, into which earth is forced as the combined three unit equipment is progressively lowered into the ground, with the progressive deepening of the well. The lower end of the housing of the core barrel unit is equipped with drilling means 102c, constructed to operate by the 90 turning of the entire unit 102. The earth is trapped in this holding chamber by means of the flexible holding strips 102d, which are shifted downwardly through the openings 102e in the wall of the said chamber, by means of the reciprocating rod 102f, similar to the one described in detail in this case. This rod is operated by a pneumatic cylinder and piston, or other means.

100 By holding the well casing at the surface against rotative movement, while permitting it to descend as the depth of the well is increased, and the electrical motor energized, the core barrel may be rotated upon its support with the motor head unit, and both the reamer and the core barrel unit held against downward displacement from the motor head unit and the well casing, by reason of the interlocking keys and keyways of the head section 5' of the well casing and the external 105 110 115 120 125 130

keys and keyways of corresponding formation carried by the housing of the motor head unit.

As the depth of the well is increased by progressive drilling, the detached material is forced into the earth holding chamber of the core barrel, and when this is filled it is withdrawn, together with the reamer and motor head unit, through the well casing, which is retained in its position in the well, to support the earth wall thereof against caving, and to provide a normally smooth tubular wall through which the combined motor head, reamer and core barrel units may be returned to the bottom of the well.

As the core barrel progressively removes the material in the path of the well bore, it is necessary to cut a circular bore of sufficient diameter to permit the free movement or easy lowering of the well casing, and this is accomplished through the medium of the reamer unit, which produces a finishing cut upon the wall of the material encountered in the passage of the core barrel through the ground.

In order to accomplish the various objects here outlined, of progressively cutting away the earth to form the well bore, and of intermittently removing the equipment, to discharge the trapped earth, it is necessary that the reamer tools be inwardly shiftable from wall cutting positions, to permit the reamer unit and the core barrel unit to be simultaneously withdrawn, with the motor head unit, from the well casing. It is furthermore necessary that the coupling between the uppermost unit, in this case, the motor head unit, and the well casing, and the construction of the housing of each of the suspended or pendant units, be of a character to permit vertical withdrawal from the head section of the well casing, and that the latter positively prevent downward displacement of the suspended units therefrom.

There are conditions in the progress of deepening a well, which may require the manual turning of the well casing from the top of the well, or its turning by any means preferred from the top of the well, so that the core barrel and the reamer units may be turned slowly in the ground, and the longitudinal interlocking between the well casing and the motor head unit permits this very operation, since the interlocking prevents relative rotative movement between the motor head unit and the well casing, and the latter and all well operating units carried thereby will be rotated whenever the well casing is turned with relation to the ground itself.

There are conditions which may require the locking of the reamer unit and the core barrel to the well casing, against vertical relative movement, or sliding, as when a percussive action is produced against the core barrel, so as to vibrate the same, or increase the drilling effect produced by its drilling

tools. In this case a locking head unit 103 is employed, which is equipped with auxiliary locking keys 103^a, which are shiftable to interlock with the transverse keyways 7a of the well casing.

To the coupling union 103^b of this coupling head, or locking coupling head, the reamer unit 101 is connected, and to the reamer unit 101 the core barrel unit 102 is connected, in the manner described with reference to Fig. 18. In this combination of units, the reamer and core barrel units are turned by the turning of the well casing, and each is operated by its own equipment, through air conduits passing upwardly to the top of the well, through the connected units and the well casing, the successive sections of which are coupled in line formation.

Where the geological matter encountered calls for the use of a shrapnel drilling unit, the system herein disclosed permits of the inclusion of such a unit in line formation, to produce a continuous automatic percussive action upon the reamer and core barrel, or upon any one or more units coupled in line formation with the shrapnel drilling unit. Referring to Fig. 20 a combination of this character is shown, which includes the shrapnel unit 104, the reamer unit 101, and the core barrel unit 102.

The shrapnel unit 104 is coupled to the well casing head section 5' against relative rotative movement, but to permit relative sliding movement, through the external keys 104^a formed on the housing 104^a of said unit, which engage the internal keys formed in the well casing head section 5'.

When the core barrel unit is used in combination with a percussive means, as, in this case the shrapnel unit 104, it is preferred that a toothed drill head 104^b, shown in Fig. 20, be employed on the lower end of the unit 104.

There are special geological conditions encountered in the drilling of some wells which suggest the use of a shrapnel drilling unit in connection with the core barrel unit, especially when considerable material of the softer grades is met with. When such material exists for a considerable depth, rapid progress can be made by eliminating the use of the reamer, and utilizing the percussive effect produced by the internal equipment or reciprocating hammer of the shrapnel drilling unit, to accelerate the drilling action of the drilling head of the core barrel. In Fig. 21 I show such a general combination, in which the core barrel unit 102 is coupled directly to the shrapnel drilling unit 104. This shrapnel drilling unit is equipped with wall drill bits 104^b, which may be expanded or retracted. Above the interlocked lower half portion of the housing 104^a of said unit 104 the means for producing the percus-

sive action are arranged in the upper half portion 104^d of said housing.

In Fig. 22 I show the motor head unit 100 combined directly with the core barrel unit 102. In this case a drilling head is used which has rotary drill bits, these being mounted on the lower end of the housing of the core barrel unit. This combination would be particularly effective in very soft ground, as the core barrel unit would be continuously rotated by the motor head unit and its enclosed reduction gearing.

In Fig. 23 I show the locking head unit 103 combined in line formation with the soft core barrel unit 102. This combination would also be used in certain conditions of drilling where considerable depth of soft materials exists, and a continuous percussive action would be maintained against the core barrel, and it would be necessary to prevent relative longitudinal movement of the core barrel on the well casing. The use of the locking head provides means whereby the core barrel can be locked to the well casing against relative 25 rotative movement and relative longitudinal movement.

As previously described the locking head is equipped with means for locking the head section 5' thereto against longitudinal movement, which consists of movable keys working through slots in the housing thereof, and which are adapted to engage the transverse keyways 7a of the well casing head section 5'. These movable keys are operated by 30 means of mechanical controls and mechanism, which can be manipulated from the top of the well.

The reamer unit, the shrapnel unit, the core barrel unit, the motor head unit, are each 40 provided with keys adapted to be longitudinally aligned with each other, and to successively pass through the keyways of the well casing head section 5', as previously described with reference to the shiftable sleeves on the housing of the core barrel units. When any one of the well 45 drilling or operating units, 100, 101, 102, 103 or 104, or all of them are coupled together and also coupled in series to the combined locking and coupling head, the shiftable external sleeve thereof is removed, so that each or all of such units carried by the combined locking and coupling head can pass through the lower end of the well casing head section 5', and be suspended thereby, without 55 danger of the working units separating from their connection with the well casing and dropping below the well casing and getting lost in the sand pockets frequently encountered in well drilling.

The reamer unit 101 is provided with an air jet 101^a or a plurality thereof, which are supplied with compressed air by means of the flexible conduit 101^b, which extends to 65 the head of the well. When the drilling

units supported by the well casing are withdrawn in stable earth or rock material, forming the wall of the well chamber below the well casing, would have a tendency to collapse, thus filling this chamber. Since 70 the withdrawal of the drilling units would take place from time to time, it is important that the wall of the well chamber below the well casing, should be supported against collapse. This object is accomplished by 75 maintaining an internal pressure against the vertical wall of the well chamber, through compressed air supplied to said well chamber by means of the jet or jets 101^a. When the drilling units are withdrawn from the well this pressure is held 80 against reduction by means of a gland joint at the head of the well casing, and a vertical enclosing cylinder, of sufficient length to accommodate the withdrawn well drilling units, which is sealed at the top.

The hereinbefore described constructions admit of considerable modifications without departing from the invention; therefore, I do not wish to be limited to the precise arrangements shown and described, which are as aforesaid, by way of illustration merely. In other words, the scope of protection contemplated is to be taken solely from the appended claims, interpreted as 95 broadly as is consistent with the prior art.

I claim as new:—

1. A well drilling apparatus comprising a core barrel having cutting means at its lower end, the core barrel being of a size to receive substantially all of the material removed by the cutting means, an anvil above and operatively connected with the core barrel, and an impact member having a cushioned support from which it is swung, said member being disposed in operative relation to said anvil to drive the core barrel by successive impacts with said anvil to effect the cutting and filling actions of the latter. 100

2. A well drilling apparatus comprising a core barrel having cutting means at its lower end, the core barrel being of a size to receive substantially all of the material removed by the cutting means, an anvil above and operatively connected with the core barrel, and an impact member disposed in operative relation to said anvil to drive the core barrel by successive impacts with said anvil to effect the cutting and filling actions of the latter, the impact element having a bodily cushioned support from which it depends and being supported above the core barrel. 105

3. A core barrel having cutters at its lower end and shaped to define a chamber for the reception of the material loosed by said cutters, the latter being positioned at the open end of said chamber, an anvil operatively connected with the core barrel, and a pneumatic hammer positioned above said anvil for delivering successive impacts to the latter 110

and thereby driving the core barrel, said hammer having a support and suspension springs by which the support is bodily carried.

5 4. A core barrel having cutters at its lower end and shaped to define a chamber for the reception of the material loosed by said cutter, the latter being positioned at the open end of said chamber, an anvil operatively connected with the core barrel, and a pneumatic hammer positioned above said anvil for delivering successive impacts to the latter and thereby driving the core barrel, the pneumatic hammer having a cushioned sup-

15 port.

5. A well drilling apparatus comprising a well casing, a housing having an interlocking connection with the well casing at the lower end of the latter to prevent relative 20 angular or turning movement between the two and likewise prevent the housing from dropping through the lower end of the casing, a core barrel open at its lower end and having cutters thereat, the core barrel being 25 interior to the casing, an anvil above the core barrel and operatively connected thereto, and an impact tool positioned in the casing above the anvil for successive impacts with the latter.

50 6. A well drilling apparatus comprising a well casing, a housing having an interlocking connection with the well casing at the lower end of the latter to prevent relative angular or turning movement between the two and 23 likewise prevent the housing from dropping through the lower end of the casing, a core barrel open at its lower end and having cutters thereat, the core barrel being interior to the casing, an anvil above the core barrel 28 and operatively connected thereto, and an impact tool positioned in the casing above the anvil for successive impacts with the latter, said impact tool comprising a bodily cushioned pneumatic hammer.

45 In testimony whereof I hereby affix my signature.

RICHARD P. SIMMONS.
